UNITED STATES PATENT OFFICE.

CORPORAL T. DONALDSON, OF COLUMBUS, OHIO.

MEASURING INSTRUMENT.

1,281,879.

Specification of Letters Patent. Patented Nov. 12, 1918.

Application filed March 28, 1917. Serial No. 158,040.

To all whom it may concern:

Be it known that I, CORPORAL T. DONALDSON, a citizen of the United States, residing at Columbus, in the county of Franklin and 5 State of Ohio, have invented certain new and useful Improvements in Measuring Instruments, of which the following is a specification.

This invention appertains broadly to the 10 measuring instrument art, and has for its primary object, the provision of an instrument for use in conjunction with the cutting of keyways in shafting and similar devices.

The invention contemplates the provision 15 of an instrument of the character described, whereby the planing or laying off of the shafting may be eliminated, by the provision of a tool which is provided with a casing or bracket member, the tool being provided further with a protractor, which may 20 be used in ascertaining the desired position of a proposed key way.

The invention may be briefly stated to 25 comprise a frame, or casing member, which is provided with a suitable recess for receiving the shafting, a clamping member for use in conjunction with the frame, whereby the same may be securely affixed or clamped to the shafting, a protractor rotatably supported upon the casing, and a 30 spirit level used in conjunction with said protractor whereby the exact positioning of the shaft may be facilitated.

All of the foregoing, together with additional, advantageous arrangement of parts 35 of the preferred embodiment of my invention will be clear from the specific description hereinafter contained, when read in connection with the accompanying drawings, forming a part hereof, wherein the preferred embodiment of the invention is 40 illustrated for the purpose of facilitating a full understanding of the present improvement.

45 In the drawings;—

Figure 1 is a front elevation; and

Fig. 2 is a transverse section therethrough taken on the lines 2—2 of Fig. 1.

Referring now more particularly to the 50 drawings, wherein like or corresponding parts are designated by like or corresponding numerals throughout the several views thereof, I provide a frame or casing mem-

ber designated in its entirety, as at 1, the casing having arranged substantially concentrically thereof a circular opening 2, which is adapted to receive and be clamped upon the shafting upon which the key ways or the like are to be cut. Within the marginal edge of the frame, adjacent the opening 2 is a key element 3, which is suitably received within a cut out portion arranged in the frame, as at 4, the purpose of which shall be subsequently apparent. The lower portion of the frame 1 is provided with a substantially square opening 5, which is adapted to receive a slidably mounted clamping block 6, the upper face of the clamping block being provided with a substantially V-shaped bearing surface, whereby the milling of the shaft to be received by said frame may be expedited. To provide for means whereby this sliding clamping member may be adjusted within the squared opening 5 and held in its adjusted position, 75 I secure to the lower face of the frame 1, a bar 7, by means of screws 8, or other suitable fastening devices. The shape of the bar 7 is such as to conform with that of the frame 1, the faces thereof being flush with the respective faces of the frame 1. A screw threaded shank member 9 is adapted to be received by the bar 7, within an interiorly threaded opening 10, the upper end of the screw threaded shank member having arranged thereon a swivel end 11, which is adapted to be engaged by the pin 12 arranged transversely of the clamping member 6, while upon its outer extremity, I provide a handle portion 13, which may be milled as at 14 in order that the same may be readily rotated. A swivel member 15 may be also threaded into one side of the frame 1, as at 16, the purpose of which shall be more fully hereinafter described.

90 Suitably mounted upon the upper face of the frame 1 and secured thereto by means of screws, or the like, as at 17, is a second housing member 18, on which is formed an outwardly extending member 19, which member is recessed as at 20, the recessed portion having arranged concentrically thereof an opening 21. Into this recess 20 I place a circular dial member 22, which is provided with, adjacent its marginal edges, 105 a series of graduations as designated at 23,

while upon the upper edge of the member 20, I place the graduation as designated at 24, the same denoting the vertical axis or plane of the shafting. Secured to the dial 22, at a point slightly below its center, is a spirit level 25, the same being supported within a suitable casing member, which in turn is secured to said dial by screws or other fastening devices 27. The dial portion 10 22 is provided with, upon its reverse face, a threaded sleeve or extension 28', which is adapted to be engaged by a thumb screw 28, which thumb screw is suitably positioned within a cut out portion 29, arranged in the 15 rear face of the element 19, and it is so positioned as to be readily rotated.

As above specified, the present invention is intended for use particularly for moving the shaft to its correct position, after a key 20 way has been formed therein, to allow the cutter to engage the shaft at a proper distance from the first formed way to form the next key way therein. Therefore, after one key way has been formed in the shaft, the 25 frame is positioned thereon and is clamped in position by the member 6 and at this time the dial is rotated to a desired number of degrees in a desired direction, measuring off from the graduation 24 the desired degree 30 upon the circular dial, with reference to the graduations on this dial. As is obvious, when the frame is clamped upon the shaft the key 3 will be fitting within the first formed key way on the shaft and for this reason the 35 frame may be swung in a desired direction by gripping the element 15 and moving the same. The swinging of the key will of course cause the shaft to be rotated in the same direction and when the bubble in the 40 spirit level is in its normal position intermediate the ends of the level, it is obvious that the same has been moved far enough with respect to the number of degrees of graduation the dial has been moved to, thus indicating that the shaft having the clamping means upon its end has been moved far enough to be disengaged by the key forming mechanism for its next operation or formation of the next key way. The frame may 45 then be removed for permitting free access to the entire length of the shaft. From this description, it should be understood that the device presented is not intended in any way to form the key way and is not carried upon 50 the shaft after the shaft has been moved to its correct positioning for the formation of a key way, but is intended to be used for facilitating the actual moving of the shaft to such a position as to permit the key way 55 forming mechanism to properly engage the shaft at the correct distance from the first formed key way where the next key way is to be formed.

It will be appreciated by workers in this 60 art, that I have provided a tool which will

dispense the heretofore intricate and laborious task of laying off shafting in order that the proper positions for cutting the key ways may be ascertained, as well as providing for a time saving instrument. Various 70 sized key ways may be milled or cut in the shafting by putting or replacing the key 3 with larger or smaller key, as conditions or preferences may dictate, within the recessed portions 4.

Different arrangements from the parts herein shown for producing the desired results may be employed together with the mechanical equivalent of some or all of said parts without departing from the spirit of 80 the invention or the scope of the appended claims.

Having thus fully described my invention, what I claim to be new and desire to secure by Letters Patent, is;—

1. A device of the character stated, comprising a frame for engagement upon a shaft, screw clamping means for securing the frame to the shaft, a rotatable protractor plate carried by said frame, a level carried by said protractor plate, a handle secured to one side of said protractor plate for facilitating rotation thereof, means arranged upon said frame whereby the shaft may be turned, and a gage key carried by the frame 95 adjacent the shaft and adapted to be received by a key way arranged in the shaft, as and for the purpose set forth.

2. In a device of the class described, the combination of a frame, means for clamping 100 said frame upon a shaft, a housing member carried upon said frame and provided with an outwardly extending member, said member having a recess formed therein, a circular dial positioned within said recess, means for retaining said dial in an adjusted set position, graduations formed on said dial and said member, thus facilitating the movement of the dial to a correct position, said frame being adapted to be shifted, and means for indicating when said frame has 105 been moved far enough.

3. In a device of the class described, the combination of a frame, means for clamping 110 said frame in an adjusted set position upon a shaft, a housing fixedly mounted upon said frame, said housing having an outwardly extending member, said member being provided with a recess formed in its forward face, said member also having a concentric opening communicating with said recess, a circular dial positioned within said recess having a sleeve connected to said dial and projecting through said opening, a thumb screw carried upon said sleeve for 115 rotating said sleeve and turning the dial to a desired position, said outwardly extending member and said dial having graduations thereon, a level carried upon said dial, thus allowing the dial to be moved according to 120 125 130

the graduations to a desired position, after which action said frame may be moved until the level indicates that the frame has been swung far enough, the frame then being re-moved, thus causing the shaft to be in proper position to allow another operation to be performed thereon.

In testimony whereof I affix my signature in presence of two witnesses.

CORPORAL T. DONALDSON.
